UNITED STATES PATENT OFFICE.

JOSEPH A. BRAUTIGAM, OF NEW YORK, N. Y., ASSIGNOR TO HIMSELF AND
F. G. JANNSCH, OF SAME PLACE.

BUTTON-HOLE SEWING-MACHINE.

SPECIFICATION forming part of Letters Patent No. 241,918, dated May 24, 1881.

Application filed August 6, 1880. (No model.)

To all whom it may concern:

Be it known that I, JOSEPH A. BRAUTIGAM, of the city, county, and State of New York, have invented certain new and useful Improvements in Button-Hole Sewing-Machines, of which the following is a specification.

The object of this invention is to furnish for tailors, manufacturers of clothing, and for family use an improved sewing-machine which 10 can be used as a common sewing-machine and for sewing button-holes, and in which the stitch can be altered while the machine is at work from a regular lock-stitch to a zigzag button-hole or embroidery stitch.

15 The invention consists of the combination, with the reciprocating needle-bar, of an adjustable cam-disk applied to and operated by an auxiliary shaft by which the needle-bar and its guide-plate are laterally oscillated simultaneously with their vertically-reciprocating motion, so as to accomplish, in connection with a slot of the needle-plate, button-hole stitching. The width of the stitch can be regulated by adjusting the cam-disk on the end of the auxiliary shaft by means of a sleeve and set-screw. The button-hole is guided for laying on the 20 stitches by a vertical pin, which is passed through a hole of the needle-plate by a slide-piece and returned below the same on the withdrawal of the slide-piece.

25 In the accompanying drawings, which fully illustrate my invention, Figure 1 represents a side elevation of a sewing-machine provided with my improvements, partly in section through the operating parts. Fig. 2 is a top view of part of the table, the work-plate, and the needle-plate of the machine; and Figs. 3 and 4 are respectively a detail end view of the needle-bar and its actuating cam-disk and 30 a detail horizontal section of the same on line xx , Fig. 3, the auxiliary shaft and thumb-screw being shown in elevation.

Similar letters of reference indicate corresponding parts.

45 In the drawings, A represents the main shaft of my improved button-hole sewing-machine; B, the vertically-reciprocating needle-bar of the same, and C a recessed guide-plate, which is pivoted to the upper part of the guide-50 casing D at the end of the supporting-arm D' of the sewing-machine. The needle-bar B re-

ceives its vertically-reciprocating motion from the main shaft A by an intermediate crank-disk and transverse slotted guide-piece, or otherwise, and moves along a recessed guide-plate, C, to which a laterally-oscillating motion is imparted by a cam-disk, E, at the end of an auxiliary shaft, E', which latter is arranged parallel to the main shaft A, and supported in bearings of the main arm D' and casing D. 55 The auxiliary shaft E' and cam-disk E receive rotary motion by a transmitting-gearing, a a' , from the main shaft A, the cam-disk engaging by a projecting cam, b , of segmental shape, the guide-plate C of the needle-bar B, so that an 60 oscillating motion is imparted to the same simultaneously with the reciprocating motion which it receives from the main shaft A. The guide-plate of the needle-bar is thrown inward by said cam, and as soon as released therefrom 65 is pressed outward by means of a spiral spring, d , which is interposed between the lower end of the guide-plate C and the casing D, as shown in Fig. 1. The cam-disk E is connected to the 70 end of the auxiliary shaft E' by a sleeve, e , which is guided by a side recess on a projecting stud, e' . The cam-disk E is adjusted on the end of the auxiliary shaft by a thumb-screw, e^2 , which bears on the outer face of the cam-disk and screws into a hole in the center 75 of the end of the auxiliary shaft E', so as to vary the laterally-oscillating motion or throw of the needle-bar B.

A spiral spring, f , is interposed between a collar, f' , of the auxiliary shaft E' and the 80 sleeve of the cam-disk E, so that on loosening the adjusting thumb-screw the cam-disk is moved outward on the auxiliary shaft until the cam b clears the guide-plate of the needle-bar. By the thumb-screw e^2 , which projects beyond 85 the face-plate of the casing D and the spiral spring f , the cam-disk E is readily adjusted on the end of the auxiliary shaft E', and thereby the stitch may be changed from a common lock-stitch to a variable embroidery-stitch 90 during the working of the machine.

The needle-plate F of the sewing-machine is attached to the bed-plate I, and is provided with a lateral slot, g , which is of sufficient length even for the extremest side motion which the 95 cam-disk can impart to the needle-bar.

For the purpose of guiding the button-hole

to the needle in stitching along the sides and around the ends of the same, a guide-pin, G, is provided, which is thrown up through a perforation of the needle-plate F, it being guided by a bracket below the needle-plate. The guide-pin G is engaged at its lower enlarged end or head by a laterally-guided slide-piece, H, which is taken hold of at its outer end by the left hand and pushed in or out, so as either to lift the guide-pin through the needle-plate or withdraw it to a level with the same, the latter motion being assisted by a spiral spring, h', interposed between the bracket h and the head of the pin, as shown in Fig. 1.

The sewing-machine may be used in the usual manner as a common sewing-machine by unscrewing the adjusting thumb-screw of the cam-disk to such an extent that the cam exerts no influence upon the oscillating guide-plate 20 of the needle-bar, in which case the button-hole attachment is entirely thrown out of use. By moving the cam-disk inwardly or turning the thumb-screw the cam of the disk engages the guide-plate of the needle-bar to a greater or less extent, so as to give the same a larger or smaller lateral throw for forming the button-hole stitches, in which case the face-gimp is supplied in the usual manner by means of a hole and guide-groove of the needle-plate, as 30 shown in Fig. 2.

The machine may be changed with great facility from a common sewing-machine to a button-hole sewing-machine, the change being accomplished by a very simple mechanism, 35 which is superior to the complicated attachments of special machines heretofore constructed for this purpose.

Having thus described my invention, I claim as new and desire to secure by Letters Patent—

1. In a sewing-machine, the combination, 40 with the main shaft and the vertically-reciprocating needle-bar, B, of the oscillating vertical guide-plate C, for carrying the needle-bar, the spring d, and the rotary disk b, operating in direct contact with the vertical guide-plate of 45 the needle-bar, said disk being adjustable, whereby it is adapted to engage the guide-plate to a greater or less extent, substantially as described.

2. In a sewing-machine, the combination, 50 with the main shaft and a vertically-reciprocating needle-bar, of an auxiliary shaft to which rotary motion is imparted from the main shaft, an adjustable cam-disk at the end of the auxiliary shaft, a guide-plate for carrying the needle-bar interposed between the needle-bar and cam-disk, and a spring for engaging with said guide-plate, substantially as described.

3. In a sewing-machine, the combination of 55 the auxiliary shaft E', having guide-stud e', 60 with a cam-disk, E, having a recessed guide-sleeve, e², and the spring f, all substantially as described.

4. In a sewing-machine, the combination, 65 with the bed-plate I and throat-plate F, of a vertical guide-pin, G, a laterally-guided slide-piece, H, for lifting the pin, and a spring for depressing the same, substantially as described. In testimony that I claim the foregoing as my invention I have signed my name, in presence of two witnesses, this 4th day of August, 1880.

JOSEPH A. BRAUTIGAM.
